UNITED STATES PATENT OFFICE.

LUTHER C. CROWELL, OF BOSTON, ASSIGNOR OF ONE-FOURTH HIS RIGHT
TO LUTHER CRANE, OF CAMBRIDGE, AND ONE-FOURTH OF HIS RIGHT
TO GALEN COFFIN, OF BOSTON, MASSACHUSETTS.

IMPROVEMENT IN PAPER-BAGS.

Specification forming part of Letters Patent No. 123,811, dated February 20, 1872.

To all whom it may concern:

Be it known that I, LUTHER C. CROWELL, of Boston, in the county of Suffolk and State of Massachusetts, have invented a new and Improved Mode of Constructing Paper-Bags; and I do hereby declare that the following is a full, clear, and exact description of the same, and taken in connection with the drawing which accompanies and forms a part of this specification is sufficient to enable those skilled in the art to make and use the same.

My invention relates to the manufacture of square-bottomed bags; and consists in so folding and cementing a strip of paper that when cut into sections of suitable length, one end being closed by one fold, the bottom of the bag or case thus formed when opened or filled will assume a quadrangular shape.

I will now proceed to describe my invention, reference being had to the accompanying drawing on which similar letters of reference in the different views indicate corresponding parts.

I consider it preferable to make a tube of paper by lapping and cementing the edges together, said tube to be made from continuous bands of paper and wound upon suitable rolls or mandrels. When said cemented edge or joint is sufficiently dry I then, by any suitable machinery, make a longitudinal lap or fold on each side of the tube, bending the same into the tube, as shown at Fig. 1, *a a* representing longitudinal folds. The tube thus folded should now be cut through the upper or lower plane, said cut extending laterally from the edge *b* to the edge *c*. The remaining portion of the tube is now severed, so as to leave the lip or end *d* projecting beyond the edges of the tube, as shown at Fig. 2. The lip or end *d* should now be covered with cement, and with a portion of

the end of the tube folded over and cemented to the opposite side of the tube, as shown at Fig. 3.

My invention is now ready for use. The mouth of the bag or case being opened the same will assume a quadrangular shape, as shown at Fig. 4; the bottom will assume the form shown at Fig. 5, which represents a plan view of the inside or upper surface of the same; and Fig. 6, which represents a plan view of the outside or lower surface of the same. A crease, *e*, made across the bag or case, as shown at Fig. 3, at such distance from the closed end as will correspond with the depth of the longitudinal folds, would determine the form which it is desired the bag or case should assume when filled, or the same result would be obtained by turning the corners *s* into the longitudinal folds, as represented by dotted lines *v v*.

I am aware that paper-bags have been made which will assume a quadrangular shape when filled; but claim the method herein described as the most simple and practical, as by this process and the proper machinery, bags which will assume a quadrangular shape can be made as economically and as rapidly as the common bags.

I claim—

As a new article of manufacture a paper bag, having two longitudinal inward folds, *a a*, terminating with a single lateral fold extending from *b* to *c*, and cemented to its body, forming the bottom, as herein shown, and for the purpose set forth.

LUTHER C. CROWELL.
